CHECK WRITER

Christian L. Rostock, Toledo, Ohio, assignor of
one-half to Walter A. Eaten, Toledo, Ohio

Application November 13, 1946, Serial No. 709,606

2 Claims. (Cl. 101—20)

1

This invention relates to selective notation marking or scarifying equipment in a compact, substantial manually operable unit.

This invention has utility when incorporated in a type carrier adapted to impress upon checks or negotiable paper the amount, as well as special supplemental indicia as may be deemed appropriate. The location and arrangement of the various manually selective features are such that an operator may use both hands to speed up the volume of work being turned out, with accuracy and clearness.

Referring to the drawings:

Fig. 1 is a side view, with the top or cover uplifted, and parts broken away, of an embodiment of the invention in a checkwriter;

Fig. 2 is a partial plan view of the unit of Fig. 1, but with the impress or scarifying-effecting handle in depressed or thrown position of operation;

Fig. 3 is a fragmentary plan view of features of the indicia or type carriers and the mounting or control parts therefor; and

Fig. 4 is a section of a portion thru the cover bridge which carries the ball stop positioning the character at the hammer for scarifying the instrument.

Housing

A pair of side strips 1, 2, have a top integral plate 3 forming a base frame having cushion feet 4. A hinge pin 5 mounts a cover or top 6 to swing from bearing-providing ears 7 near one end of the base 1, 2, 3. Intermediate the length and from the lower side, the cover 6 has clearance region 8 to span the outwardly projecting overhang portions of the plate 3, which may serve as a check-receiving table. A knob 9 on a pin 10 may direct the pin 10 thru an opening 11 of the cover 6 and openings 12 in the sides 1, 2, as aligned to enter internally threaded opening 13. The checkwriter unit is thus locked in closed position for operation. As so assembled, it is convenient for shifting about as desired.

Hammer

From this closed housing, thru an upwardly extending slot 14 of skirt portion 15 of the top 6 remote from the hinge pin 5, is an arm 16 having a handle or terminus 17. From this outer terminus 17, the arm 16 extends along inside the frame side 1 and is rockably mounted on a shaft 18 extending between the sides 1, 2, of the frame, spaced somewhat down from the plane of the

2

plate 3 and clear thereof toward the skirt portion 15.

The arm 16 has integral therewith a cam short arm 19 against which rides a long arm 20 fixed on a shaft 21 between the sides 1, 2. Also fixed with the shaft 21 and oppositely extending from the arm 20 toward an opening 22 in the plate 3, is an arm 23 having crosswise and upwardly open from its free end a channel 24 in which is located an impactor or hammer face of a desired degree of hardness, as a hard rubber 25.

Ribbon feed and ribbon

Fixed with the arm 20 is a short arm 26 from which upwardly extends a resilient metal strap or thrust pawl 27 coacting with a ratchet wheel 28 fixed with a spool 29 on the shaft 18 upon which the lever 16, 19 is loosely mounted. As the handle 17 is depressed, and this actuation transmitted by the arm 19 to the arm 20, the pawl 27 moves downward over the teeth of the wheel 28. Inwardly extending from the frame side 1 above the shaft 18 is a lug 30 from which extends a tension helical spring 31 to an upstanding lug 32 medially of the arm 16. Accordingly as the handle 17 is released, the spring 31 swings the arm 16 upward to its initial or starting position. The channel 24 and its rubber head 25 are retracted by a spring 31' to cause the arm 20 to ride closer to the shaft 18 during the recovery of the arm 16. This rocking of the arm 20 upward, causes the pawl 27 to thrust against the wheel 28 with sufficient force to advance or give a step rotation. This causes the spool 29 to take a step in wrapping inking band or ribbon 33 thereon.

Near the opposite ends of the plate 3 are guides 34, 35, for the ribbon 33. A supply spool 36 for the ribbon 33, is mounted on stub shafts 37. In order that the intermittent pulling of the ribbon 33 to the spool 29 may not cause excess turning of the spool 36, there is a brake 38 to hold it back.

Check locator

45 A knob 39 is on a shaft 40 in the side frames 1, 2, parallel to the shaft 37 on the side thereof away from the hinge pin 5. Upwardly extending from and fixed with the shaft 40 are fingers 41. The fingers 41 extend thru slots 42 in the plate 3. A spring plate 43 about the shaft 40 adjacent the frame side 1 provides frictional resistance to hold the fingers 41 at a set adjustment of the knob 39 as to indicating scale 44 for a pointer 45 fixed with the knob 39. The operator of the checkwriter may turn the knob 39 to ad-

just the position of the fingers 41 so that a check as pushed across the plate 3 under the ribbon 33, may have its top edge ride against the fingers 41, in order that the region thereof may be marked to be in the range of the hammer 25. When the operator has the fingers 41 so adjusted that the inserted check has the marking region thereof at the hammer 25, the operator may note where the pointer 45 is on the scale 44 and thereby have available a definite setting for the like checks.

Indicia mounting and control

The cover 6 has an open top region 46. Slightly inwardly offset from the bounds of the region 45 is a plate 47. The cover 6, above the clearance region 8 has a guide block portion 48. This portion 48 is below the plate 47 at the portion of the plate 47 toward the hinge pin 5. In addition to the block portion 48, the cover 6 has an additional block portion 49. The block portion 48 is near the top end of the cover skirt portion 15. Parallel guide rods 50 are fixed in these blocks 49, 48, and in extending from the block 49 pass on thru the block 48 to project therebeyond.

Inasmuch as the rods 50 are to guide, the element to be guided is assembled with each rod 50 before the rod 50 is anchored in the block portions 48, 49. The element to be guided comprises an upright leg 51 parallel to a leg 52 with a connecting base portion 53. Each unit 51, 53, 52 is of a general U-form or shape. In the assembly of the U-element with its rod 50, the leg 51 is on the portion of the rod 50 which projects from the block portion 48 on the side away from the block portion 49. The other leg 52 is on the rod 50 between the blocks 48, 49. The U-element is thus directed to slide along the rod 50 as a guide with the portion 53 parallel to the rod 50 and therebelow.

Above the respective rods 50 and in line therewith thru the plate 47 is a slot 54. In alignment with each of these slots 54 in the plate 47 and toward the end of the plate 47 remote from the block portion 49, is a small port or window 55. Each of the legs 52 protrudes upward thru a slot 54 and has mounted thereon a knob 56.

The block 48 is spaced slightly away from the plate 47 and provides a clearance 57 between the upper side of the block 48 and the underside of the plate 47. Just inward from the slot 54 each leg 52 has a strip 58 extending to ride thru the clearance 57 in the extent of the strip 58 to the leg 51 on the same rod 50 as the leg 52 of the element 52, 53, 51, to which the strip 58 is also connected. The strip 58 is thus parallel to the portion 53. Upon the side of each strip 58 away from the portion 53, is a series of notations 59. Useful function resides in this strip 58, for the reason that the notations 59 thereon as exposed to the window 55 are identical with the notation to be acted upon by the hammer 25.

The base portion 53 of the element or unit 51, 53, 52, riding on each of the guide rods 50, has on its side toward the rod 50 a series of seats or notches 60. Upon its opposite or under side, the portion 53 has mounted thereon an indicia carrier or type bar 61. Type or characters 62 are ribbed or of scarifying effecting form on the bar 61. As one of these characters, say "7" is located at the hammer 25 thru operation of the knob 56 on one of the U-elements 52, 53, 51, the strip 58 for such element exposes at its window 55, the character "7." A definite holding of the

slidable unit 52, 53, 51, to have its character 62 as elected, register with the hammer 25, is brought about due to the notch 60 corresponding to such character 62 being engaged by a ball 63, yieldably thrust into the notch 60 as a seat by a spring 64. There is in the block 48 a ball 63 thrust toward each base 53 by a spring 64. The spring 64 is a helical compression spring in an opening in the block 48 thru which opening the rod 59 holds the spring 64 compressed for the element 51, 53, 52, having the particular base 53 engaged by the ball 63. There is thus provided a yieldable stop permitting the checkwriter operator to take hold of a knob 56 and thrust it along its slot 54 for disclosing a desired marking numeral or notation 59 at its window 55. Again considering that the character "7" be so placed, its location is over and directly against the top side of the ribbon 33 as extending across the opening 22 in the plate 3 and is directly opposite the hammer 25. The characters to be marked upon an instrument 65 on the plate 3 (Fig. 4) are individually selected thru the manipulation of the knobs 56. When these are fully assembled, the operator then pushes the handle 17 downward and the hammer 25 imparts the upward impact to the back of the instrument to be marked. There may be a slight give or yield in this hammer action to the extent there be looseness of the legs 51, 52, on the rod 50, or resiliency in the rod 50, to allow the frame portion 53 to rise snugly against the under side of the block 48. The recover of the handle 17 automatically effects a slight advance of the inking means. This provides fresh or renewal of the pigment depositing means upon the check. Clarity in the marking is thus had with no requirement for attention upon the part of the operator, except to replace the inking strip or ribbon 33 as in its runs thru the machine it becomes too much worn to warrant reversal.

A spring strap pawl 66 engages the ratchet wheel 28 and limits the direction of turning of the wheel 28 to that of the thrusting by the pawl 27.

What is claimed and it is desired to secure by Letters Patent is:

1. A checkwriter cover indicia carrier comprising a pair of legs with a connecting base portion to form a U-frame, a guide rod thru the legs of the frame, said cover having a block portion between the legs thru which portion the rod extends to slidably carry the frame with the legs on opposite sides of the block portion, a notation strip extending between the legs and over the block portion toward the cover, said connecting portion of the frame between the legs having a succession of seats therealong toward the block portion, and an indicia carrier along the opposite side of the connecting portion of the frame and a spring ball catch in the block portion between the rod and a seat to register thereunder and a hammer impactor opposing said selected seat.

2. A checkwriter including a base, a cover therefor, a handle, a first fulcrum for the handle, said first fulcrum having pivot bearing in the base, a cam-carrying arm fixed with the handle, a second fulcrum having bearing in the base axially parallel to and spaced from the first fulcrum, a lever mounted on the second fulcrum and adapted to be actuated by the cam, said lever having an arm provided with an impactor bar at its free end, a pawl mounted directly on the lever remote from the bar, a ratchet with which the

pawl coacts, a pigment strip mounted in the base and connected to be shifted relatively to the bar by said ratchet, selective notation means carried by the cover and thereby held toward the opposite side of the strip from the bar, an adjustable guide way for an object to be marked, said way providing a station between the notation means and strip at the vicinity of the bar, and spring means normally retracting the handle from bar impacting operation toward the notation means, and during said retracting coacting thru said lever to shift the strip thru operating the pawl and ratchet.
